Patented Apr. 4, 1922.

Inventor
Jacob Stander.

Attorney

W. G. Houtain

UNITED STATES PATENT OFFICE.

JACOB STANDER, OF BROOKLYN, NEW YORK.

SIGNAL FOR AUTOMOBILES.

1,411,755.

Specification of Letters Patent. Patented Apr. 4, 1922.

Application filed June 12, 1920. Serial No. 388,675.

To all whom it may concern:

Be it known that I, JACOB STANDER, a citizen of the United States, and resident of Brooklyn, in the county of Kings and State 5 of New York, have invented certain new and useful Improvements in Signals for Automobiles, of which the following is a specification.

The present invention relates to signalling 10 devices, particularly safety devices for attachment to automobiles.

The invention has for its principal object the provision of means, carried by an automobile and under control of its chauffeur or 15 driver, for warning drivers of other vehicles traveling rearwardly of him as to his intentions, by indicating his arbitrarily selected purposed course, whereby liability of collision is obviated; a further object being to 20 provide a device of this character which is successfully operable under daylight or dark night conditions.

The above named and other objects are attained by employing a plurality of semaphores, means for mounting and operating 25 said semaphores and means for illuminating them, and other novel features hereinafter fully described and specifically set forth in the annexed claims.

30 In the accompanying drawings forming part of this specification, Figure 1 is a face view of my improved device showing one of the semaphores raised to its position of warning. Fig. 2 is a similar view showing the several semaphores partly raised. Fig. 3 is a 35 sectional view taken on the line 3—3 of Fig. 4. Fig. 4 is a sectional view taken on the line 4—4 of Fig. 3. Fig. 5 is a view showing a means for operating the levers; and Fig. 6 40 is a fragmentary view of part thereof.

In the embodiment of my invention illustrated by the drawings, 1 indicates a sheet metal casing embodying front and rear walls 2, 3 and side walls 4; said casing being 45 mounted on a suitable standard 1^a adapted for attachment in any suitable manner to the rear or to any desirable part of an automobile.

50 Swingly mounted within the casing 1, are semaphores 5, 6 and 7, preferably three in number and shaped like a human hand and forearm; these semaphores are respectively fulcrumed on a common pivot 8 extended laterally across the upper part of the casing 55 1, and they are respectively provided with a

short lever-extension 9, to which is pivoted the upper end of a rod 10; these rods, at their respective lower ends, are in pivotal relation with levers 11, which swing on a common pivot 12 and are respectively provided with 60 an outwardly extended part 13, for connection with a means for imparting a downward swing to the lever 11, as a rod, cord chain or other device 14, adapted to lead to a point adjacent the chauffeur, whereby he may control and operate the semaphore. 65

In pivotal relation with a pin 15, extended across the upper part of the casing 1, is a compound curved swinging door 16, whose inner surface bears on the semaphores 5, 6 70 and 7, whereby said door may be swung upwardly by any one of said semaphores; said door having a flange 17, at each side which clasp over the casing 1 when the door is in its closed or downwardly extended position, to 75 prevent lateral oscillations of said arm.

Carried on the free end of the door 16, is an electric lamp 18, whose feed wires 19 and 20 may lead to a suitable source of electric current supply carried by the vehicle, the 80 current adapted to be controlled by any suitable switching means which may be operated by the chauffeur.

I do not confine myself to the employment of any specific switching means, nor to a specific means for operating the levers 11, as I believe that I am entitled to use various devices of a character adapted for ready manipulation by the chauffeur or driver of a vehicle to which my improvement may be attached. 85 90

The semaphores are each provided with a printed warning or announcement, preferably the word "stop" on the semaphore 5; the word "right" and an arrow pointing to 95 the right on the semaphore 6; and the word "left" and an arrow pointing to the left on the semaphore 7.

I may employ any desirable means for transmitting movement to the levers 11; in 100 Figures 5 and 6 I have shown a compound lever device comprising a two-armed lever 21, fulcrumed on a fixed pivot 22, one arm of said lever pivoted to a rod 23 which is in pivotal engagement with the lever 11, and the 105 other in pivotal engagement with a rod 24, which engages a member 25, of a crank 26 which is provided with a handle 27 for operating the crank; said crank being journaled through hangers 28 which may be suit- 110

ably fixed on the rod 29 of a steering wheel of an automobile, or to any suitable part of the vehicle to which the device is attached.

In the operation and use of the invention, 5 when a chauffeur decides to stop his machine he pulls the lever 11, which operates the semaphore 5, downwardly, this movement being transmitted to the semaphore 5, by means of its connecting rod 10, swings said 10 semaphore upwardly and outwardly until it assumes a position at right angles with the casing 1, as indicated by Fig. 1 of the drawings, thus indicating to any drivers located rearwardly of him that the intends to stop, 15 the same operation being employed in relation to each of the other semaphores, depending on his intention to turn either to the right or left. At night when the chauffeur operates the semaphores he also switches on a 20 current of electricity to light the lamp 18; thus the device may be successfully employed as a means for warning adjacent chauffeurs, either in daylight or darkness, to obviate liability of accidents and collisions.

25 Having thus described my invention, what I claim as new and desire to secure by Letters Patent, is:

1. A vehicle signalling apparatus adapted for both day and night use comprising a 30 plurality of swinging semaphores having each a different printed warning thereon,

casing means for said semaphores, and separate lever and connecting-rod means for operating said semaphores in succession, and a swinging door adapted for operation by any 35 one of said semaphores, said door being gravity closable and having a lamp which is obscured within the casing when the door is closed.

2. In a signal apparatus of the character 40 described, the combination with a plurality of normally depending oscillatable signalling semaphores, and lever and connecting-rod means for independently operating them; of a door adapted to be closed by its 45 own gravity, said door adapted to be opened by any one of said semaphores.

3. In a signal apparatus of the character described, the combination with a plurality of normally depending semaphores having 50 each a printed warning thereon for daylight use, and a casing, and lever and connecting-rod means for individually operating said semaphores, of a gravity closable swinging door having a lamp which is normally obscured within said casing, said door adapted to be opened by any one of said semaphores.

Signed at New York city in the county of New York and State of New York this eleventh day of June A. D. 1920.

JACOB STANDER
